UNITED STATES PATENT OFFICE

SAMUEL HUSE, OF CHICAGO, ILLINOIS.

ROTARY ENGINE.

Specification of Letters Patent No. 22,955, dated February 15, 1859.

To all whom it may concern:

Be it known that I, SAMUEL HUSE, of Chicago, in the county of Cook and State of Illinois, have invented a new and Improved 5 Rotary Steam-Engine, of which the following is a full, clear, and exact description, reference being had to the accompanying drawings, making part of this specification, in which—

10 Figure 1 is a side elevation, a portion of the outer shell or casing being broken away. Fig. 2 is a transverse vertical section on the line x, x , of Fig. 1. Fig. 3 is a view, the outer shell and cylinder being both removed 15 to show the parts within.

That others skilled in the art may understand and use my invention I will proceed to describe the manner in which I have carried out the same.

20 In the drawings A, A² are heads supported on feet a the shaft B to which the power of the engine is applied being passed through these heads in suitable stuffing boxes. Between the two heads A, A² is a cylinder C, 25 the flanches b of which are attached to the heads by screws c . Over the periphery of the flanches b fits an outer shell or casing D, an annular space or steam chamber being thus formed between the shell and the cylinder C. This annular steam chamber is divided into two portions e, e^2 , by a longitudinal partition f at the top of the cylinder which extends along on the outside of the cylinder C from one flanch b to the other 30 and also by a partition g , which starts from a point 5 on one flanch b and winds spirally half way around the outside of the cylinder to the other flanch at the opposite end of it. These partitions are steam tight, and the 35 spaces e, e^2 communicate the one e with the induction pipe at h , and the other e^2 with the eduction or exhaust at i , as indicated by the arrows Fig. 2. The heads A, A² and cylinder C are stationary the parts which 40 form the valves and pistons being connected with the shaft B and revolving within the cylinder as will now be explained.

To the heads A, A² are secured on the inner side and projecting into the cylinder 50 C screw cams E, E² of the form shown in Fig. 3 and detached in Fig. 4, the cam E, on the head A being placed with its thickest or highest portion 6, opposite to the thinnest portion 7 of the cam E² on the head A².

55 The shaft B carries a heavy cylindrical hub F, the ends of which are recessed into

and revolve in the space h , (Fig. 4,) in the middle of the cams E, E². To this hub F are secured two rings or heads m, m^2 of such a diameter that they shall revolve steam 60 tight within the cylinder C, while the face or side of each runs in close contact with the higher portion 6 of the cams E, E². This leaves a steam space between each of the heads m, m^2 and the inclined face of the adjacent cam E or E², the space gradually 65 enlarging toward the thinner portion 7 of the cam.

Three grooves are cut radially in the hub F for the whole of its length, corresponding 70 slots being cut through the heads m, m^2 . Into each of these grooves and slots are inserted two pistons or valves n, n^2 , which slide longitudinally in the grooves, their outer ends being kept in close contact with the faces of the cams E, E² by a spring b , placed between the two valves (see Fig. 3). These valves are of such a width that the inner edge rests on the bottom of the groove in the hub F and the outer edge projects out 75 on a line with the periphery of the heads m, m^2 , as shown in Fig. 2. As before stated the cams E, E² are so placed with respect to each other that the thick part of one shall be opposite the thin part of the other, the 80 distance in a straight line parallel to the shaft B from different portions of the face of one cam to the face of the opposite cam being equal. The valves n, n^2 will as 85 the shaft B and hub F are revolved remain 90 in contact with the surfaces of the two cams and also with the inner surface of the cylinder C. Steam is not admitted into the space 95 between the two heads m, m^2 but only between these heads and the faces of the cams E, E². Each of these cams has cut in it on the 100 thicker side holes o, p , which enter from the edge which is in contact with the cylinder C' and come out on the face of the cam (Fig. 4,) forming steam and exhaust ports. Corresponding holes o', p' , in the cylinder 105 C establish a steam communication between the spaces e, e^2 on the outside of the cylinder C, and the spaces 8 between the heads m, m^2 and the cams E, E². The spiral partition g allows the holes p' at the opposite ends of the cylinder C to both outlet into the space e^2 although placed on opposite sides of the cylinder and in the same way the holes o' to communicate with the space e . 110 The operation of this engine is as follows: Steam enters through the inlet pipe h to

the steam space e , thence through the holes o' , o , to space 8, between the head m and cam E , and behind the valve n , which happens to be in position to receive the pressure of the steam by which this valve is driven in the direction of the arrow on the head m , Fig. 3 and the shaft B is revolved; the steam continues to act on this valve n until cut off from it by the next valve passing the port o . The valves are thus acted upon in succession by the steam, and as each one passes the port p the steam exhausts through this port into the space e^2 on the outside of the cylinder C , and thence through the eductor pipe i as indicated by the arrows. A similar state of things is going on at the opposite end of the cylinder, except that the valves are in an inverse position. The engine is reversed by changing the current of steam, and causing it to

enter at the pipe i and exhaust at the pipe h in the customary manner.

This engine like many others of its class is adapted for use as a pump or water engine. I have heretofore spoken of this engine as constructed with three sets of valves n , n^2 ; it may however be made with a greater or less number as circumstances may require. 25

What I claim as my invention and desire 30 to secure by Letters Patent is—

The cams E , E^2 with their steam and exhaust ports in combination with the heads m , m^2 pistons n , n^2 and cylinder C , operating in the manner substantially as 35 herein set forth.

SAML. HUSE.
